DESIGN FOR A SUPPORT HEAD FOR A VEHICLE JACK

Donald A. Dalton, Warsaw, Ind., assignor to The
Dalton Foundries, Inc., Warsaw, Ind., a cor-
poration of Indiana

Application March 10, 1941, Serial No. 99,456

Term of patent 14 years

To all whom it may concern:

Be it known that I, Donald A. Dalton, a citizen of the United States, residing at Warsaw, in the county of Kosciusko and State of Indiana, have invented a new, original, and ornamental Design for the Support Head for a Vehicle Jack, of which the following is a specification, reference being had to the accompanying drawing, forming a part thereof.

Figure 1 is a perspective view of a support

head for a vehicle jack embodying my new design.

Fig. 2 is a longitudinal central section through said support head.

Fig. 3 is an end elevational view thereof.

I claim:

The ornamental design for a support head for a vehicle jack, substantially as shown.

DONALD A. DALTON.
